SPORT BOOT

Joseph P. Famolare, Jr., Florence, Italy, assignor to Famolare, Inc., New York, N.Y.

Filed Apr. 15, 1974, Ser. No. 461,005

Term of patent 14 years

Int. Cl. D2—04

U.S. Cl. D2—311

FIG. 1 is a right front perspective view of a sport boot showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof;

FIG. 7 is a rear elevational view thereof; and

FIG. 8 is a right front perspective view of another embodiment of my new design of FIGS. 1-7 wherein hooks have been substituted for eyelets.

I claim:

The ornamental design for a sport boot, substantially as shown and described.
